UNITED STATES PATENT OFFICE.

DAVID S. SHUTTS, OF NEW BRIGHTON, PENNSYLVANIA.

SHADE AND CURTAIN BRACKET.

No. 879,684.

Specification of Letters Patent.

Patented Feb. 18, 1908.

Application filed August 23, 1907. Serial No. 389,878.

To all whom it may concern:

Be it known that I, DAVID S. SHUTTS, a citizen of the United States of America, residing at New Brighton, in the county of Beaver and State of Pennsylvania, have invented certain new and useful Improvements in Shade and Curtain Brackets, of which the following is a specification, reference being had therein to the accompanying drawing.

10 This invention relates to improvements in shade and curtain brackets, and the invention has for its object to provide adjustable brackets for supporting a curtain pole and a curtain shade roller, the brackets being constructed whereby they can be easily and quickly adjusted to fit window-frames, alcoves or door-ways of various sizes.

My improvement consists in providing two adjustable members that can be easily lengthened or shortened to correspond to the width of the window-frame or even to project beyond the edges thereof. Each member carries a movable casing, serving as a hanger for the members and as a curtain shade roller bracket. At the outer end of each member I detachably secure curtain pole brackets, these brackets being dispensed with when the improvement is simply employed for holding a curtain shade roller.

30 The detail construction entering into my invention will be presently described, and then specifically pointed out in the appended claims.

Referring to the drawings, Figure 1 is a perspective view of a bracket, Fig. 2 a rear elevation of one end of the bracket, and Fig. 3 is an edge view of a modified form of curtain pole bracket.

In the accompanying drawings, 1 and 2 designate rigid metallic strips, the end of the strip 1 being provided with a keeper 3 for receiving the member 2, while the end of the member 2 is provided with a similar keeper 4 for receiving the member 1. These keepers are riveted or otherwise secured to the members, and are adapted to maintain said members in longitudinal alinement and permit of their adjustment.

50 Slidably mounted upon the outer ends of said members are metallic casings 5, said casings having flanged edges embracing the members and constituting keepers 6. The outer end of the casings carry curtain shade roller brackets 7, one of said brackets being

slotted as at 8, while the other of said brackets is apertured, as at 9, the slot 8 and aperture 9 receiving the pintles of a curtain shade roller.

The casings 5 carry upwardly extending hanger lugs 10, provided with inverted key-hole shaped openings 11, whereby the shade and curtain bracket can be suspended from the nails or screws (not shown) carried by a window-frame or similar support.

The extreme outer ends of the members 1 and 2 carry headed lugs or pins 12 upon their rear faces, said pins or lugs being used for detachably holding curtain pole brackets 14. These brackets may extend upwardly at an angle to the members 1 and 2, or may extend outwardly at right angles as illustrated in Fig. 3 of the drawings, therefore I do not care to confine myself to the type of curtain pole bracket which is detachably secured to the ends of the members 1 and 2. In order to attach the brackets 14 to the members 1 and 2, the ends of the brackets are slotted as at 15, to receive the pins or lugs 12, the heads thereof engaging the slotted ends of the brackets, and preventing said brackets from being detached, except by an upward movement of the same.

The shade and curtain bracket in its entirety is constructed of light and durable metal and by making the same adjustable, I aim to secure a wide range of utility, principally because window-frames, curtain poles and curtain shade rollers vary in size. It is possible by my improvement to accommodate shade rollers and curtain poles of different lengths, thereby not necessitating the altering of curtain shade rollers and curtain poles, when the same do not exactly fit a window-frame.

I attach considerable importance to the detachable curtain pole brackets, as in a great many instances, lace curtains and draperies are not used when curtain shades are employed.

Such variations and modifications of my invention as are permissible by the appended claims can be resorted to without departing from the spirit and scope of the invention.

Having now described my invention what I claim as new, is:—

In a shade and curtain bracket, the body thereof formed of two parallel bars overlapped at one end, a keeper carried by the

inner or overlapping end of each bar and receiving the other bar, a rectangular casing slidably-mounted on each bar and having the longitudinal edges thereof flanged to embrace the bar, an upwardly-extending hanger-lug carried by each of said casings, a shade-pole bracket formed integral with one end of each casing and projecting forwardly at right an-

gles to the casing, and a curtain pole bracket carried by the outer end of each of said bars. 10

In testimony whereof I affix my signature in the presence of two witnesses.

DAVID S. SHUTTS.
